T. H. DAVIS

Des. 162,012

ASH TRAY

Filed June 3, 1949

Fig. 2.

UNITED STATES PATENT OFFICE

162,012

ASH TRAY

Thomas Herman Davis, Brooklyn, N. Y.

Application June 3, 1949, Serial No. 3,029

Term of patent 3½ years

(Cl. D85—2)

To all whom it may concern:

Be it known that I, Thomas H. Davis, a citizen of the United States of America and resident of Brooklyn, county of Kings, State of New York, have invented a new, original, and ornamental Design for an Ash Tray, of which the following is a specification, reference being had to the accompanying drawing, forming a part thereof, in which

Fig. 1 is a top plan view of an ash tray embodying my design; and

Fig. 2 is a front elevational view thereof.

I claim:

The ornamental design for an ash tray, as shown.

THOMAS HERMAN DAVIS.
